UNITED STATES PATENT OFFICE.

FRANK M. SINCLAIR, OF INDIANAPOLIS, INDIANA.

WASHING-MACHINE SUPPORT.

No. 893,879.

Specification of Letters Patent.

Patented July 21, 1908.

Application filed May 7, 1907. Serial No. 372,360.

To all whom it may concern:

Be it known that I, FRANK M. SINCLAIR, citizen of the United States, residing at Indianapolis, in the county of Marion and 5 State of Indiana, have invented certain new and useful Improvements in Washing-Machine Supports, of which the following is a specification.

This invention appertains to a laundry appliance designed for supporting a tub, and means for agitating clothing or articles to be cleansed without subjecting the same to rubbing or pounding which tends to weaken the fabric and to tear the same.

15 The invention combines a support for the suds receptacle and sustaining means for the washer, the latter comprising coöperating complementary rolls which are forced together by spring pressure to admit of their yielding 20 to the bulk of the clothing or fabric passing between them.

For a full description of the invention and the merits thereof and also to acquire a knowledge of the details of construction and 25 the means for effecting the result, reference is to be had to the following description and accompanying drawings.

While the invention may be adapted to different forms and conditions by changes in 30 the structure and minor details without departing from the spirit or essential features thereof, still the preferred embodiment is shown in the accompanying drawings, in which:

35 Figure 1 is a perspective view of the machine set up for use. Fig. 2 is a perspective view showing the device closed. Fig. 3 is a detail perspective view showing more clearly the means for supporting the rollers comprising the washer.

The stand portion comprises bars 1 which are connected by rungs 2, 3 and 4. Other bars 5 considerably shorter than the bars 1 are pivoted intermediate of their ends to 45 the said bars 1 by means of the rung 4. The bars 5 are adapted to turn freely upon the rung 4 and are connected near their ends by rungs 6 and 7. The bars 5 are arranged upon the inner sides of the bars 1. Other bars 8 50 are pivotally connected with the bars 1 by means of the rung 3 and are formed with longitudinal slots 9 through which the rung 6 connecting the upper ends of the bars 5 passes. The bars 8 are connected at or near 55 their outer ends by means of a rung 10 and are arranged upon the inner sides of the bars 5.

The parts are so arranged as to admit of the bars 5 and 8 folding into the plane of the bars 1. Notches 11 are formed in the inner or rear edges of the bars 5 to receive the rung 3 and thereby admit of said bars 5 being turned when folded to lie wholly in the plane of the bars 1 so as to occupy the smallest amount of space. When the bars 5 are unfolded, they are limited in their outward movement by the rung 6 engaging with the outer ends of the slots 9. The bars 8 with the coöperating rungs 3, 6 and 10 form a support for a tub or suds receptacle 12, said support occupying an approximately horizontal position. The bars 5 with their connecting rungs and the bars 1 with their connecting rungs, form in effect folding leg sections of the main frame and support the washer and the suds receptacle.

75 Bars 13 are pivotally mounted upon the rung 2 and are connected by means of rungs 14 and 15. Plates 16 are pendent from the outer ends of the bars 13 and support a roller 17. Springs 19 are secured at 80 their inner ends to the bars 13 by means of fastenings 20 and their outer ends are crimped to receive the journals of a roller 21 which coöperates with the roller 17. A crank handle 22 is fitted to the roller 21 for 85 convenience of rotating the same when the machine is in operation. Set nuts 23 mounted upon the threaded ends of bolts 24 engage with springs 19 and regulate the tension thereof to force the roller 21 against the 90 roller 17 with a greater or less degree of pressure to suit the clothing or articles to be laundered.

In practice, when the leg sections of the frame-work or stand are unfolded, the support for the tub or suds receptacle occupies an approximately horizontal position and receives the said tub or receptacle. The washer is adjusted so that the rollers come over the tub or suds receptacle with the lower 100 roller 17 dipping into the water. The clothing to be washed is passed between the rollers 17 and 21 either in a continuous direction or backward and forward, the compressive force exerted by the rollers 105 removing the dirt from the meshes of the fabric by forcing the water therethrough, the same carrying off the dirt or foreign matter.

When the machine is to be set aside and 110 is not required for immediate use, the leg sections and the support for the tub are

folded into the plane of the bars 1 and the washer is folded against the frame-work or stand thus reduced to compact form.

Having thus described the invention, what is claimed as new is:

A wash bench comprising pivoted leg sections, one of the leg sections being longer than the other and each leg section being of similar construction and comprising side bars 10 and connecting rungs, a support having pivotal connection with the longer leg section and comprising side bars having longitudinal slots through which passes a rung near the

top of the shorter leg section, the parts being arranged to fold into a common plane, and 15 bars pivotally connected to the upper end of the longer leg section, and adapted to be held in an approximately horizontal position to form a support for a clothes washer.

In testimony whereof I affix my signature 20 in presence of two witnesses.

FRANK M. SINCLAIR. [L. s.]
